UNITED STATES PATENT OFFICE.

JOHN SAM IRICK, OF CHICAGO, ILLINOIS.

TRAY-HOLDER FOR TRUNKS.

No. 838,861.

Specification of Letters Patent.

Patented Dec. 18, 1906.

Application filed April 4, 1906. Serial No. 309,895.

To all whom it may concern:

Be it known that I, JOHN SAM IRICK, a citizen of the United States, residing at Chicago, in the county of Cook and State of Illinois, 5 have invented a new and useful Tray-Holder for Trunks, of which the following is a specification.

The invention relates to improvements in tray-holders for trunks.

10 The object of the present invention is to improve the construction of tray-holders for trunks and to provide a simple, inexpensive, and efficient device adapted to be readily applied to the tray of an ordinary trunk and capable when the tray is swung upward from a horizontal to a vertical position of automatically supporting it in the latter position.

15 A further object of the invention is to provide a tray-holder of this character which may be readily operated for releasing the tray to permit the same to be swung downward to a horizontal position within the body of the trunk.

20 With these and other objects in view the invention consists in the construction and novel combination and arrangement of parts hereinafter fully described, illustrated in the accompanying drawings, and pointed out in the claim hereto appended, it being understood that various changes in the form, proportion, size, and minor details of construction within the scope of the claim may be resorted to without departing from the spirit or sacrificing any of the advantages of the invention.

25 In the drawings, Figure 1 is a perspective view of a trunk provided with a tray-holder constructed in accordance with this invention. Fig. 2 is an enlarged sectional view illustrating the construction of the tray-holder and showing the same in engagement with the upper edges of the body of a trunk. Fig. 3 is a detail sectional view taken substantially on the line 3 3 of Fig. 2.

30 Like numerals of reference designate corresponding parts in all the figures of the drawings.

35 11 designate a pair of spring-actuated rods which are mounted on a tray 2 of a trunk by means of spaced intermediate and end supports 3 and 4 and which are adapted when the tray is swung upward to the position illustrated in Fig. 1 of the drawings to be thrown outward automatically into engagement with the upper edges of the body 5 of

the trunk, whereby the tray is supported in an elevated position for affording free access to the body of the trunk. The tray is designed to be hinged at the upper edges of its back at 6 in the usual manner, and the supports are applied to the rear lower edge of the tray, as clearly shown in Figs. 1 and 3 of the drawings. The supports are provided with angularly-disposed attachment-flanges 7 and 8, which receive the edge of the tray 65 and which fit against the outer faces of the rear wall and bottom of the tray, being secured to the same by screws, rivets, or other suitable fastening devices. The intermediate support 3 is preferably arranged at 70 the center of the rear lower edge of the tray, and it is provided at its angle with a tubular guide 9, which receives the inner end portions of the rods 1. The inner ends of the rods are angularly bent to form a pair of operating-handles 10, which are arranged in a bottom slot 11 of the intermediate support 3.

75 The outer supports 4 are preferably arranged at the ends of the tray, and they are provided at their angles with tubular barrels or casings 12, which form housings for coiled springs 13. The ends 14 of the barrels or casings are preferably reduced to fit the rods 1, and the springs, which bear against the inner ends of the barrels or casings, engage projections 15 of the rods. The 80 projections are preferably formed by pins, which pierce the rods, as shown. The springs are compressed when the tray is in a horizontal position within the body of the 85 trunk, and they are adapted to throw the rods outward automatically into engagement with the upper edge of the body of the trunk when the tray is swung upward above the same. The handles are located in convenient positions to enable them to be simultaneously grasped for withdrawing the rods from engagement with the body of the trunk to permit the tray to be swung downward.

90 Having thus fully described my invention, what I claim as new, and desire to secure by Letters Patent, is—

95 A tray-holder for trunks comprising spaced intermediate and end supports provided with angularly-disposed attachment-flanges arranged to receive the edge of the tray, the intermediate support being provided at the angle formed by the flanges with a tubular guide and having a slot, and the end supports being provided at their angles with 105 110

barrels or casings, rods passing through the barrels or casings and having their inner portions supported by the said guide and provided at their inner ends with terminal handles operating in the said slot, and springs housed within the barrels or casings for automatically throwing the rods outward when the tray is swung upward.

In testimony that I claim the foregoing as my own I have hereto affixed my signature to in the presence of two witnesses.

JOHN SAM IRICK.
